SILENT MAGNETIC SWITCH

Igor Zozulin and George J. Okulitch, Vancouver,
British Columbia, Canada

Application October 22, 1951, Serial No. 252,482

Claims priority, application Canada
August 13, 1951

3 Claims. (Cl. 200—67)

1

This invention relates to electric switches and in particular to electric switches in which the operation is induced by a permanent magnet.

In electrical switches and particularly electric switches used to control domestic lighting systems it is the practice to use a construction comprising a series of levers, linkages and toggles to effect the making and breaking of the circuit. These toggles and levers are moved by the operator from an external point and are held in their two normal positions by means of springs. It was found that this type of switch, with its many moving parts experienced great wear at critical points and that after a limited period of use its operation was erratic and undependable. The pivot joints between the levers became worn and allowed an amount of play between the two parts that was sufficient to destroy the positive action of the switch. The springs which urged the contact points into or out of engagement also lost their strength after a short time and the operation of the switch was seriously impaired.

The feature of this invention lies in the use of a permanent magnet as the urging means in place of the springs of the old type of switch and in the method of constructing the switching mechanism so as to reduce the number of parts and thereby the number of points of wear. The switch that is the embodiment of the present invention cannot wear out and is virtually noiseless.

An object of this invention is to provide an electric switch which makes use of a permanent magnet in place of springs.

A still further object of this invention is to provide an electric switch which can be hermetically sealed against moisture and dust.

A still further purpose of this invention is to provide an electric switch, the operation of which is virtually noiseless.

A still further purpose of this invention is to provide an electric switch which will be actuated by the slightest pressure on a flexible plastic diaphragm.

A still further object of this invention is to provide an electric switch which will indicate at a glance whether the switch is in the "on" or the "off" position.

These and other salient objects of this invention will be apparent from the following description and claims when read in conjunction with the appended drawings of which:

Figure 1 is a plan view of the preferred embodiment of the invention.

Figure 2 is a section view through section line A—A of Figure 1.

2

Figure 3 is a plan view of another embodiment of the invention.

Figure 4 is a section view taken through section line A—A of Figure 3.

Referring now to Figures 1 and 2 it will be seen that the switch is of standard size and will fit into the conventional wall box. The outer casing 1 of the switch is of a dielectric material and is in the form of a rectangular box, open at one face. Inside the box 1 at one corner is mounted a permanent magnet 2 held in place by a screw 3 which does not penetrate through the wall of the box 1. The magnet 2 is C-shaped and has its north and south poles, N and S respectively, facing each other in spaced relationship. To the left of the magnet 2 is the switching beam 4 which is made of Bakelite or other dielectric material. The beam 4 is mounted on a pivot 5 in such a position as to enable the projection 6 of beam 4 to lie between the poles of the magnet 2. The end of the projection 6 which is between the poles of the magnet 2 is composed of a magnetic metal 7, such as iron to enable it to adhere to one or the other of the poles of the magnet. The beam 4 is provided with an electrical contact point 8 mounted on a projection of the beam 4 extending in the opposite direction from the magnetic projection 6. This electrical contact point 8 is in abutment with a second electrical contact point 9 when the switch is in the "on" position. At the top of the dielectric box 1, i. e. the open side, there is a diaphragm 10 provided with two cylindrical protuberances 11 and 12. The diaphragm 10 completely covers the open end of the box 1 and is secured there in such a manner as to hermetically seal the switching mechanism against moisture and dust. On the beam 4, on the side of the pivot 5 remote from the magnet 2 and the contact point 8 are two cylindrical protuberances 13 and 14 of unequal height, the higher one, 14 being of a height sufficient to enable it to touch the diaphragm 10 directly beneath the outer protuberance 12 when the magnetic end 7 of the beam 4 is adhering to the N pole of the magnet 2. When the member 7 is adhering to the S pole of the magnet 2 the beam 4 will have rotated about the pivot 5 to such an extent that the lower protuberance 13 has been elevated until it touches the diaphragm 10 directly beneath the outer protuberance 11. In this position, since the beam 4 has rotated slightly the beam 4 has caused the metallic end 7 to move to the neutral position between the magnetic poles. At that moment the contact points 8 and 9 are still in abutment because of the spring

action of the mounting member 29. As the beam 4 is in this position the magnetic end 7 of said beam is half way between the N and S poles of the magnet 2. At this point magnetic attraction is altered and the end 7 is sharply attracted to the other pole of the magnet to the S pole thus breaking the contact instantaneously. The contact point 8 mounted on the beam 4 by means of a metal projection 15 which is in turn connected electrically by means of a flexible conductor 28 to a screw terminal 16 on the exterior surface of the box 1. The screw 16 is on the outside of the box 1 and is threaded into a metal plug 17 which passes through the walls of the box 1 and is sealed therein so as not to disturb the moisture proof qualities of the box. The contact point 9 is secured by means of a metallic spring 18 directly to a metallic plug 19, similar to the plug 17, the plug 19 also being provided with a screw terminal 20. At each side of the dielectric box 1 is a metallic angle bracket 21 and 23 for the purpose of securing the switch to a standard wall box 21 by means of screws 22 and 23. A standard push button switch cover plate 24 is placed over the diaphragm 10 to complete the assembly and is held in place by screws 25 and 26.

When the switch is connected to a circuit the conductors are secured to the screws 16 and 20. When the metallic end 7 of the projection 6 adheres to the N pole of the permanent magnet 2 the contacts 8 and 9 are touching and the protuberance 14 is touching the diaphragm 10 directly beneath the cylindrical protuberance 12 on the diaphragm 10. Since the contacts 8 and 9 are touching the circuit is complete or the switch is in the "on" position. When the protuberance 12 is pressed it transmits the pressure to the protuberance 14 and pushes it down. This motion moves the metallic end 7 of the projection 6 and it snaps over and adheres to the S pole of the permanent magnet 2 thus moving the contact 9 away from contact 8 thus breaking the circuit. At the same time the protuberance 13 is moved up until it touches the diaphragm 10 directly beneath the protuberance 11. The switch is then in the "off" position. Pressure on the protuberance 11 will reverse the process.

In a second embodiment of this invention as illustrated in Figs. 3 and 4 shows the mechanism of the switch in closed circuit position (Fig. 4). The mechanism is mounted in a rectangular box 1a made of a dielectric material, the box 1a being open at its upper face. Following assembly of the switch parts inside the box 1a, a flexible diaphragm 2a of transparent plastic is fitted over the open face of the box and hermetically closed so that the switch mechanism is sealed against dust and moisture. A second rectangular box 3a is provided, similar in construction to standard type switches, to house the dielectric box 1a and to provide mounting means for the switch. Brackets 4a and 5a are pressed into dielectric box 1a and screws 6a and 7a are provided to attach the dielectric box 1a to the outer box 3a. A cover plate 8a provides a front face for the switch and protects the flexible diaphragm 2a against any possible damage. Screws 9a and 10a are provided to hold the cover plate 8a in place. A cylindrical protuberance 11a is formed integrally on flexible diaphragm 2a, this protuberance 11a extending through an opening in the cover plate 8a.

The components to be mounted inside dielectric box 1a, comprise a permanent magnet 12a which is fastened to an end face of dielectric box 1a by

means of fastening screw 13a. A moving beam 14a constructed of a dielectric material is pivotally mounted on shaft 15a so that the beam can oscillate about the axis of shaft 15a. The ends 5 of shaft 15a are sealed into box 1a. A sleeve 16a is mounted on beam 14a to provide bearing surface with shaft 15a and to prevent lateral movement of beam 14a. Armature pieces 17a and 18a of a ferromagnetic substance are secured to the end of beam 14a adjacent the N and S pole faces, which faces are shown sloping in order to obtain maximum contact with the armature pieces 17a and 18a. The other end of beam 14a carries a switch contact 19a and electrical means of connection are provided between contact 19a and a flexible conductor 20a. The other end of conductor 20a is attached to outlet contact 21a which has a screw 22a to which outside circuit connection can be made. A resilient arm 23a of conducting material is provided having contact 24a fixed at its end in juxtaposition to contact 19a and outlet contact 21a with screw 26a is provided for outside circuit connection at the opposite end of the resilient arm 23a. Attached 10 to beam 14a and preferably formed integrally with it are two curved branch arms having knobs 27a and 28a to engage in the small cavities in member 29a. Member 29a is substantially cylindrical in shape except for the slight flange at its lower end in which the two cavities are formed. This member 29a is attached by pin 30a to the under side of protuberance 11a, so that pressure on the protuberance 11a unit be transmitted through diaphragm 2a and the member 29a to the knobs 27a (or 28a) and hence to actuate beam 14a.

To provide indication for off or on position of the switch, a curved arm 31a is shown being a part of beam 14a and when the curved arm is in the position indicated in dotted lines the end of the arm will show as a spot on the transparent diaphragm. This spot will disappear with the downward movement of arm 31a indicating that the switch is in closed circuit position.

The operation of the switch is very simple as slight finger pressure on protuberance 11a causes deflection of the diaphragm 2a which in turn causes member 29a to press downwards on the knob 27a and thereby forces armature 17a to break contact with the N pole of magnet 12a. As the switching beam 14a is pressed downwards the magnetic end 17a moves to the neutral position between the N and S poles of the magnet. Contact points 19a and 24a are still in abutment because of the spring action of the mounting member 23a but the attraction of the S pole becomes great enough at this point to cause end 17a of beam 14a to snap over sharply breaking the contact instantaneously. Armature 18a is then contracted by the S pole of magnet 12a which holds the switch in open position. To close the switch a very slight pressure again on protuberance 11a repeats the above operation with the difference that the pressure is now transferred to knob 28a causing the armature 18a to break away from the S pole of magnet 12a and the attraction of the N pole results in the switch being again placed in closed circuit position.

We claim:

1. An electric switch hermetically sealed within an insulating box open at one side, by a flexible diaphragm, a permanent magnet having a north pole and a south pole facing each other across a gap, a beam carrying an armature at one end and an electrical contact at the opposite end

pivottally mounted within said casing, the said armature extending into the gap between the said north and south poles, said electric contact on said beam making contact with an electric contact on the wall of said box when said armature adheres to said north pole and said contact on said beam separating from said contact on said box when said armature adheres to said south pole, a protuberance on said diaphragm comprising a button, a pressure and motion transmitting member on the side of the diaphragm remote from said button and arms on said beam to contact said pressure transmitting member.

2. An electric switch as claimed in claim 1 in which the said arms on said beam are separated by the said pivot and only one arm contacts said pressure and motion transmitting member at a time.

3. An electric switch as claimed in claim 1 in which said flexible diaphragm is capable of distortion in a direction at right angles to its plane a distance equal to slightly more than one half the distance between the said north pole and the said south pole of the said magnet.
